UNITED STATES PATENT OFFICE.

EMORY GLENN SIMPSON, OF DETROIT, MICHIGAN, ASSIGNOR TO TERNSTEDT MANUFACTURING CO., OF DETROIT, MICHIGAN, A CORPORATION OF MICHIGAN.

CURTAIN-ROLLER.

1,344,358.

Specification of Letters Patent. Patented June 22, 1920.

Application filed September 8, 1919. Serial No. 322,241.

To all whom it may concern:

Be it known that I, EMORY GLENN SIMPSON, a citizen of the United States, residing at Detroit, in the county of Wayne and State 5 of Michigan, have invented certain new and useful Improvements in Curtain-Rollers, of which the following is a specification.

This invention relates to curtain rollers, and has for its object a curtain roller assembly which is made almost entirely from stamped parts that can be assembled without the necessity of solder, welding or similar fastening means. The roller is provided with a clutch which is assembled without 10 riveting and which is noiseless. This clutch is also located near the middle of the roll where it is not likely to be jammed by dropping and is out of reach of dust. This and other objects will better appear when the 15 roller construction is fully understood.

In the drawings,—

Figure 1 is a longitudinal section of the roller and its supporting brackets.

Fig. 2 is a section on the line 2—2 of 25 Fig. 1.

Fig. 3 is a section on the line 3—3 of Fig. 1.

Fig. 4 is a section on the line 4—4 of Fig. 1, detailing the clutch.

Fig. 5 is a section on the line 5—5 of Fig. 1.

Fig. 6 is an end elevation of the right hand felt washer cup shown in Fig. 1.

a designates the barrel of the curtain 35 roller which is provided with the lock seam *b*. *c*, *c* designates the two curtain roller brackets which are provided with short hollow studs *d*, each of which has a struck-in spur *e* for the purpose of engaging the 40 halved end *f* of the curtain roller rod. These hollow studs serve to hold the curtain roller rods non-rotatably in the brackets when the brackets are slipped over the halved outer ends of the rods and screwed to the support.

45 Instead of having a single curtain rod that extends from end to end through the barrel, as is customary, a two-part rod formed by the rod *g* and the rod *h* is employed. This results in economy in material and is a most

50 useful arrangement from the standpoint of large production. The rod does not always have to be produced to fit the barrel, that is, the barrel may vary in length and yet the same curtain rods used to mount the roller.

Each curtain rod *g* and *h* has a ring boss *i* 55 upset thereon to hold the other parts longitudinally in place. For instance, taking the left hand end of the roller, a sheet metal plug and washer retainer *j* fits into the left hand end of the barrel, is doubled upon 60 itself to form a flange *k* to guide the curtain, and is turned in at its center to form a hub *l* that engages the outside of the boss *i*. A pair of felt washers *m* are securely fixed in this retainer when the lip *n* is turned 65 down; hence when the inner washer is forced over the boss *i*, this end of the barrel is securely secured to the rod *g*. The same construction is used at the opposite end of the barrel except that an additional cup *o*, 70 detailed in Fig. 6, is pinched in. This cup *o* is provided with a pressed-in spring-seat *q*, which would be a complete annulus except for the two straps *r* that are not punched in with the spring-seat. This seat is adapted 75 to accommodate the last turn of the torsional spring *s* and hence act as a spring abutment. The two straps *r* afford something to which the end of the spring may be fastened, while the other end of the spring 80 is secured to the rod *h* running through the perforation *t*. *u* is a blotting-paper lining for the barrel adjacent the spring to deaden 85 any possible clashing of the spring with the barrel.

An intermediate support of the barrel upon one of the curtain roller rods *g* is provided by the washer retaining cup *v*, which is provided with a turned-over lip *x* to retain the two felt washers *y*.

The cup *z* has a lip 1 turned over to inclose a gravity dog-carrier 2, detailed in Fig. 4, and containing a pair of guide slots 3 in which can rise and fall the gravity dogs 4. These dogs are housed on one side by the 90 walls of the slots of the dog-carrier and the other by the cup *z*. The rod *h* is cut away at its inner end and provided with a longitudinal slot in the cut-away portion, which is V-shaped in cross section as shown at 95 5, Fig. 3. This slot has approximately a 135 degree opening, while the point of the pawl is a right angle.

Referring to Fig. 4, it will be seen that the guide slot 3 does not run radially but on 100 relatively long chords. This arrangement, together with the 135 degree opening of the dog-engaging slot 5, is such that gravity

causes the one dog that happens to stop above the slot to drop in the same and the energy of the spring tends to pull the dog against the right hand side wall of the slot 5, and jam the dog against this side wall. However, when a downward pull is exerted on the curtain, which would be a counter-clockwise movement of the dog-carriers shown in Fig. 4, the bottom of this dog 10 strikes the opposite wall of the slot 5 and the dog is simply forced outwardly in its guide and ceases to act as an impediment to the turning of the dog-carrier; hence the dog-carrier and the barrel of the roller can 15 always turn in a contrary direction to the exertion of the spring but they cannot turn in the same direction as the exertion of the spring except when the movement is rapid enough to prevent the pawl falling down. 20 into the V-groove. Obviously when the curtain is pulled down slightly and then allowed to move upwardly quickly, the dog has not the time to drop into the V-groove but is also restrained from dropping by centrifugal force. This arrangement makes an 25 obvious improvement over the usual pawls that are riveted on to a pawl-carrier and which require an upsetting operation and are quite liable to become loosened or 30 clamped. The clutch is thus located near the middle of the roll out of reach of dust and in a position where it is little likely to be jammed by dropping the roll.

It will be noted that the end plugs j , the 35 cups for the washers, and the clutch cup z , are all provided with recesses, of which such a one as shown at 6 in Fig. 6 is an example. This is to receive the lock seam of the barrel and also acts as a key to key these various 40 members to the barrel. This does away with spot-welding, soldering or otherwise fastening the parts. They are tightly fitted into the barrel so as to prevent any unnecessary longitudinal movement, while the key non- 45 rotatably ties them to the barrel.

What I claim is:

1. A curtain roller, having in combination, one or more rods for supporting the same, a barrel supported on the rod and 50 provided with a lock seam, and one or more cups provided with washers and supported in the barrel and having a recess in the pe-

riphery to engage the lock seam of the barrel as a key.

2. In a curtain roller, the combination 55 with a rod provided with a dog-engaging recess, of one or more free but sliding and guided gravity dogs arranged in connection with the recess to be jammed when turning in one direction and to be forced out of the 60 recess when turning in the opposite direction, and means for so supporting the dogs about the rod.

3. In a curtain roller, the combination 65 of a rod provided with a longitudinal recess therein V-shaped in cross section, a dog-carrier provided with a dog-guide, and an unattached dog slideable in the dog-guide, the parts being so arranged that when the dog-carrier rotates in one direction the dog 70 jams against one wall of the recess of the rod and when the dog-carrier rotates in the opposite direction the dog strikes the opposite wall of the recess and is caused to withdraw outwardly in the dog-guide. 75

4. In a curtain roller, the combination of a rod provided with a recess in the end thereof, a disk-like dog-carrier provided with a guide disposed on long chords of the disk, a dog slideable in the guide, the recess being arranged so that when the disk-like 80 dog-carrier rotates in one direction the dog jams against one wall of the recess and when the disk-like dog-carrier rotates in the opposite direction the dog is forced outwardly 85 in the guide to allow such rotation of the dog-carrier.

5. In a curtain roller, the combination of a rod provided with a slot therein V-like in 90 cross section, a disk-like dog-carrier comprising a pair of guides disposed on long chords of the disk at opposite sides of the center, and dogs slideable one in each guide, substantially as described.

6. In a curtain roll, the combination of a 95 rod provided with a recess, a barrel, a dog-carrier located near the longitudinal middle of the barrel, and a dog supported by the dog-carrier and adapted to engage the recess of the rod when the roll rotates in one direction slowly. 100

In testimony whereof I affix my signature.

EMORY GLENN SIMPSON.
